UNITED STATES PATENT OFFICE.

CHARLES BASKERVILLE, JR., OF NEW YORK, N. Y.

DESIGN FOR A MAT.

Application filed December 12, 1928. Serial No. 29,234. Term of patent 14 years.

To all whom it may concern:

Be it known that I, CHARLES BASKERVILLE, Jr., a citizen of the United States, residing at New York, in the county and State of New York, have invented a new, original, and ornamental Design for Mats, of which the following is a specification, reference being had to the accompanying drawing, forming part thereof.

The figure is a plan view of a mat showing my new design.

I claim:

The ornamental design for a mat as shown.

CHARLES BASKERVILLE, JR.
